UNITED STATES PATENT OFFICE

FREDERIC J. RODE, OF CHICAGO, ILLINOIS

SHEET METAL DRAWING PRESS

Application filed June 10, 1932. Serial No. 616,371.

This invention relates in general to sheet metal drawing presses, but more particularly to the blank or work holding means thereof.

5 Heretofore in presses of the character in which the work is formed between co-operating dies, one of which is reciprocable towards and away from the other, there is provided a blank or work holder which co-operates 10 with one of the dies for clamping or holding the work while the latter is being formed by the dies.

It has been customary to provide a resiliently yielding cushion, embodying a pressure pad, operating upon the work holder to cause 15 the material to be gripped or clamped with sufficient pressure to permit the material to "flow" during the shaping operation, and at the same time prevent the work from wrinkling, but not with sufficient pressure which 20 would cause the material to become ruptured in the shaping operation.

It has been found that for various reasons 25 and at times, such for instance, if the die is not arranged centrally of the base, or when it is desired to perform one operation on one side of the center of the base, in which the blank or work holder is necessary, and another and different operation on the other 30 side of the center where the blank holder is not necessary, unequal pressures will be exerted upon different parts of the pressure pad, with the result that there is a tendency 35 for the pressure pad, as well as the work holder to tilt, causing the work to be gripped with unequal force at different points of the work holder, which is not desirable for obvious reasons.

40 It is one of the objects of the present invention to provide improved means for maintaining the pressure pad and the blank or work holder against a tilting movement under the stress of the operation of the ram upon the work, and to maintain a uniform pressure or gripping of the blank or work holder throughout the entire area thereof.

45 A further object is to provide improved means operatively associated with the blank or work holder and the pressure pad, which will, when one portion of the holder or pad

is depressed, cause the remaining portions thereof to be correspondingly depressed and thereby maintain the pressure pad as well as the blank holder in a level or horizontal position.

To the attainment of these ends and the accomplishment of other new and useful objects as will appear, the invention consists in the features of novelty in substantially the construction, combination and arrangement 50 of the several parts hereinafter more fully described and claimed and shown in the accompanying drawings illustrating this invention and in whch

55 Figure 1 is a view partly in elevation, partly in section, with parts broken away and with parts omitted, of a press of this character constructed in accordance with the principles of this invention.

60 Figure 2 is a view taken on line 2—2, Figure 1, with parts broken away.

65 Figure 3 is a detail sectional view taken on line 3—3, Figure 2.

70 Referring more particularly to the drawings the numeral 10 designates generally the base of a press, having uprights 11 and provided with a ram 12 which is reciprocated in guides 13 on the uprights 11 by means of links 14 connected to the source of power.

75 Carried by the ram is a die 15 and arranged within the base 10 of the press is a cushioning device, preferably in the form of a closed chamber 16 having tubular members 17 projecting thereinto and reciprocable in these tubular members are pistons 18 upon which a 80 pressure pad 19 located below the bed or bolster plate 20 of the press rests. Secured to the bed of the press is a die 21 with which

85 the die carried by the ram 12 co-operates and encompassing the die 21 is a blank or work holder 22 supported by means of pins 23 which pass loosely through the bed plate 20 and engage and rest upon the pressure pad 19. Fluid pressure in the chamber 16 tends 90 normally to hold the pressure pad 19 against the lower face of the bolster or bed plate 20, causing the upper surface of the blank or work holder 22 to be maintained normally and substantially flush with the upper surface of the die 21, so that the work 24 will 95 100

be supported upon the die and the work holder.

All of the above referred to parts are of the ordinary and well known construction.

- 5 It has been found that in many instances when the ram 12 is lowered to contact with the work 24 and as the work holder co-operates with the die 15 to clamp the work while the latter is being formed or shaped, there 10 is an unequal pressure at different points about the area of the blank or work holder as the latter is depressed to lower the pressure pad 19 against the fluid pressure in the chamber 16. This unequal pressure causes the 15 blank or work holder 20 to tilt and this tilting movement will be imparted to the pressure pad 19, with the result that unequal gripping pressure will be exerted upon the work.
- 20 Even though such a tilting movement of the pressure pad and the blank or work holder may be of small degree, the same would be objectionable and would be sufficient to cause injury to the work.

- 25 In the present invention means have been provided for overcoming or preventing such tilting movement and such means operates in a manner that when one portion of the blank or work holder 22 or pad 19 is depressed such 30 movement will cause the remaining portions of the blank or work holder to be correspondingly depressed.

To that end the bed of the press may be recessed as at 25 so that the pressure pad 19 35 may move therein.

Arranged along the end walls of the recess are racks 26 which are laterally spaced from each other for any suitable distance, and any number of these racks may be provided.

40 Arranged along the front and rear walls of the recess are racks 27, any suitable number of which may be provided on each of the walls and are laterally spaced from each other.

45 Journaled in suitable bearings 28 carried by the pressure pad and arranged therebelow so as to extend across the ends of the pressure pad are shafts 29 secured to each of which are gears 30 which mesh with the respective 50 racks 26.

55 Journaled also in suitable bearings 31, which latter may if desired be portions of the bearings 28, and extending along the front and rear edges of the pressure pad and therebelow are shafts 32, and secured to these shafts 32 are gear wheels 33 which are arranged adjacent and mesh with the respective racks 27.

60 The shafts 29 and 32 are so arranged that they will not interfere with each other and are also so arranged that they will not interfere with the operation of the pistons 18, as portions of the pistons may, if desired, be cut away so as to accommodate the shafts 32.

65 With this improved construction it will be

manifest that no matter at what point pressure from the ram may be applied to either the blank or work holder 22 or the pressure pad 19, the pressure pad 19 will be maintained in a horizontal or level position for the reason that even though the pressure is applied to the pad adjacent one edge or one side thereof, the pressure pad will be lowered and this lowering movement will cause the gears to move over the respective racks and as the gears are operatively connected to the respective shafts, the rotation of the shaft will cause each of the gears to move an equal distance over the respective racks thereby operating to "pull down" the portion of the pressure pad which is remote from the point at which the pressure of the ram is applied.

70 In other words, no matter where the pressure is applied to the pressure pad to force it down, the gears and racks will cause the pressure pad to always be maintained in a horizontal position and each portion of the pad will move an equal distance under the force or pressure exerted thereupon by the ram.

75 As soon as the ram starts to recede the fluid pressure in the chamber 16 will operate upon the pistons 18 to move the pressure pad 19 together with the work or blank holder 22 back to their normal position, the gears moving over the respective racks to permit of such return movement.

80 While the preferred form of the invention has been herein shown and described, it is to be understood that various changes may be made in the details of construction and in the combination and arrangement of the several parts, within the scope of the claims, without departing from the spirit of this invention.

85 What is claimed as new is:—

1. In a press, a reciprocable ram, a fixed die, a work holder, means embodying a pressure pad for yieldingly resisting the movement of the work holder in one direction, and means connected with said pad and operating when pressure is exerted upon one portion of the pad to move it against said resisting means, to cause another portion of the pad to be correspondingly moved to maintain the pad against tilting.

thereof to move the pad, the portion of the pad on the other side of such center will be correspondingly moved and the pad will aright itself and will be maintained against 5 tilting.

4. In a press, a pressure pad adapted to be lowered during the operation of the press, and gear and rack connections between the pad and bed of the press whereby when pressure is exerted upon one portion of the pad to lower the same another portion of the pad remote from the point of greatest pressure will be correspondingly lowered to maintain the pad against tilting.

15 5. In a press, a pressure pad adapted to be lowered during the operation of the press, and gear and rack connections between the pad and bed of the press whereby when pressure is exerted upon one portion of the pad to

20 lower the same another portion of the pad remote from the point of greatest pressure will be correspondingly lowered to maintain the pad against tilting, said gear and rack connections being housed within the bed of

25 the press.

30 6. In a press, a pad adapted to be lowered during the operation of the press, spaced gears carried by the pad below the surface thereof, and spaced racks secured to the press frame and over which racks the respective 35 gears move, said gears and racks operating to maintain the pad against tilting during its movement under pressure, regardless of the point or area of the application of such pressure upon the pad.

35 7. In a press, a pad adapted to be lowered during the operation of the press, and means operating automatically to maintain said pad against tilting during its movement under 40 pressure regardless of the point or area at which said pressure is applied to said pad.

45 8. In a press, a pad adapted to be lowered during the operation of the press, and positively operating means operating automatically to maintain said pad against tilting during its movement under pressure regardless of the point or area at which said pressure is applied to said pad.

50 9. In a press, a pressure pad adapted to be lowered during the operation of the press by pressure exerted thereupon, and means operating automatically to neutralize any tendency of the pad to tilt during its movement under such pressure, regardless of the point or area of such pad at which such pressure is applied.

55 10. In a press, a pressure pad adapted to be lowered during the operation of the press by pressure exerted thereupon, and means operating automatically to neutralize any tendency of the pad to tilt during its movement under such pressure, regardless of the point or area of such pad at which such pressure is applied, said means embodying gear

and rack connections between said pad and a stationary part of the press.

11. In a press, a pressure pad adapted to be lowered during the operation of the press by pressure exerted thereupon, means operating automatically to neutralize any tendency of the pad to tilt during its movement under such pressure, regardless of the point or area of such pad at which such pressure is applied, the said means embodying spaced gears carried by and arranged along the ends of the pad, spaced gears carried by and arranged along the front and rear edges of the pad, and upright stationary racks secured to stationary parts of the press and over which racks said gears move.

In testimony whereof I have signed my name to this specification, on this 16th day of May, A. D. 1932.

FREDRICH J. RODE. 85
